(57) **CLAIM**

The ornamental design for a rocker switch as shown and described.

DESCRIPTION

FIG. 1 is a top left perspective view of a rocker switch. FIG. 2 is a front elevational view of the rocker switch depicted in FIG. 1.

FIG. 3 is a rear elevational view of the rocker switch depicted in FIG. 1.

FIG. 4 is a left-side elevational view of the rocker switch depicted in FIG. 1.

FIG. 5 is a right-side elevational view of the rocker switch depicted in FIG. 1.

FIG. 6 is a top plan view of the rocker switch depicted in FIG. 1.

FIG. 7 is a bottom plan view of the rocker switch depicted in FIG. 1; and,

FIG. 8 is a top left perspective exploded view of the rocker switch depicted in FIG. 1.

The broken lines in the drawings illustrate portions of the rocker switch that form no part of the claimed design and depict environmental subject matter only.

1 Claim, 8 Drawing Sheets
